UNITED STATES PATENT OFFICE.

EDWARD DOUBLE, OF LOS ANGELES, CALIFORNIA.

ROTARY BIT.

1,182,533.

Specification of Letters Patent. Patented May 9, 1916.

Application filed June 17, 1914. Serial No. 845,582.

To all whom it may concern:

Be it known that I, EDWARD DOUBLE, a citizen of the United States, residing at Los Angeles, in the county of Los Angeles and State of California, have invented a new and useful Rotary Bit, of which the following is a specification.

In rotary bits in which a plurality of rotary cutters are mounted on the lower end 10 of the body, the cutters being inclined so that their cutting portions come rather close together, it is found that the detritus is apt in some formations to accumulate underneath the body between the cutters and form 15 an impediment to the free downward passage of the tool, and it is the object of the present invention to provide a novel and effective means for obviating this difficulty.

Referring to the drawings: Figure 1 is 20 a side elevation of a bit constructed in accordance with my invention. Fig. 2 is a longitudinal sectional view through the bit. Fig. 3 is an end elevation of the lower end of the body. Fig. 4 is a side elevation in 25 detail of one of the cutters.

1 designates the drill body provided with a tapered lower end on which are rotatably mounted a plurality of cutters 2 in such a manner that the cutting edges of the cutters come rather close together at the bottom. In the present case I have shown two cutters 2, arranged opposite each other, but the precise number of cutters employed is immaterial to the invention. I have found 35 in practice that the detritus is in some formations apt to collect between the lower cutting edges of the cutters underneath the body 1, and pack therein to a greater or less extent, and thereby prevent the free 40 downward movement. Detritus is apt to pack therein in such a manner as to make it difficult to dislodge it in the usual manner by the entering stream of water which flows down through the cutters 3 formed in the

45 body 1, and discharges from branches 4 at the lower end of the body 1. The feature of the present invention is to construct the cutters 2 with openings or perforations therein at such a point as to allow the detritus which lodges in the space between the cutters to be discharged laterally outward 50 through the openings in the cutters by being washed therethrough by the entering stream of water from the water courses 4. The exact form and arrangement of the perforations is immaterial. In the present case I have

shown an outer row of perforations 5 and an inner row of larger perforations 6. These perforations are preferably with tapering walls 7, the smaller diameter of which is on the inside of the cutter, so that material which is forced into the inner end of the perforation will readily pass through the perforation without packing therein as the diameter of the perforation increases toward 65 the outer ends.

In the present case the cutters are shown with plain circular cutting edges 8, but the exact form of cutting edge is not essential. As before stated, the detritus is apt to pack 70 between the cutters at a point above the cutting edges thereof, and for this reason the perforations are preferably arranged at a point inward from the cutting edge of the cutters sufficient to receive the detritus from 75 points above the cutting edges.

By constructing the cutters in this manner with numerous small perforations, the necessary openings are produced for the passage of detritus without weakening the cutters, and the bit as thus constructed will operate freely in all formations without the detritus choking into the space between the cutters and retarding the progress of the 80 drill.

The manner in which the cutters are secured to the body is immaterial. In the drawings I have shown the cutters as mounted on studs 9, which are screwed in the body 1, and are locked in place by a 90 curved bolt 10 which passes completely through both studs 9. The cutters are preferably mounted on bushings 10' with washers 11 and 12 arranged on both sides of the 95 bushings.

What I claim is:

1. In a rotary bit, a body with a wedge shaped lower end, a pair of rotatable cutters mounted on the lower end with the lower edges of the cutters close together, the body being provided with a water course for conducting water into the space between said cutters at the lower end of the body, said cutters being provided with perforations to permit the passage of detritus from said 100 space directly outward through the cutters.

2. In a rotary bit, a body and rotatable cutters mounted on the lower end of the body and having their lower ends closer to each other than their upper ends, said body 110 having a water course therein discharging between the cutters, said cutters having per-

forations therein to permit the passage of detritus from the space between the cutters.

3. In a rotary bit, a body and rotary cutters mounted on the lower end of the body and projecting below the lower end thereof, said cutters having perforations formed therethrough communicating the outer faces thereof with the space below the lower end of the body between the cutters, 10 and said body having a water passage formed therein discharging into the space below the lower end thereof between the cutters.

4. In a rotary bit, a body and rotary cutters mounted on the lower end of the body and projecting below the lower end thereof, said cutters having perforations formed therethrough communicating the outer faces thereof with the space below the lower end 15 of the body between the cutters, and said body having a water passage formed therein discharging into the space below the lower end thereof between the cutters, said cutters having their lower ends located in closer relation to one another than their upper ends.

5. In a rotary bit, a body and rotary cutters mounted on the lower end of the body and projecting below the lower end thereof,

said cutters having openings formed therethrough communicating the outer faces 30 thereof with the space below the body and between the cutters, said openings being tapered and enlarged at their outer ends, said body having a water course therethrough discharging at the lower end of the 35 body between the cutters.

6. In a rotary bit, a body and rotary cutters mounted on the lower end of the body and projecting below said lower end, said cutters converging toward their lower end 40 and having rows of openings formed therethrough communicating the outer faces thereof with the space below the lower end of the body between the cutters, one of said rows of openings being larger than the 45 other, and said body having a water course therethrough discharging between the cutters below the lower end of the body.

In testimony whereof, I have hereunto set my hand at Los Angeles, California, this 50 12th day of June, 1914.

EDWARD DOUBLE.
